(57) **CLAIM**

The ornamental design for a viewing wheel with swing arm amusement ride as shown and described.

DESCRIPTION

FIG. 1 Is a perspective view of a viewing wheel with swing arm amusement ride.

FIG. 2 is a left side elevation view thereof.

FIG. 3 right side elevation view thereof.

FIG. 4 is a back side elevation view thereof.

FIG. 5 is a front side elevation view thereof.

FIG. 6 is a top view thereof; and,

FIG. 7 is a perspective view of the viewing wheel with swing arm amusement ride of FIG. 1 with the only difference being the swing arm in an alternate configuration.

The features shown in broken lines depict portions of the viewing wheel with swing arm amusement ride that form no part of the claimed design.

1 Claim, 7 Drawing Sheets
